OR D 11,850

Design No. 11,850, dated July 6, 1880.

UNITED STATES PATENT OFFICE.

WILLIAM C. PEET, OF JERSEY CITY, NEW JERSEY, ASSIGNOR TO THE J. L. MOTT IRON WORKS, OF NEW YORK, N. Y.

DESIGN FOR A FIRE-PLACE.

SPECIFICATION forming part of Design No. 11,850, dated July 6, 1880.

Application filed May 31, 1880. Term of patent 3½ years.

To all whom it may concern:

Be it known that I, WILLIAM C. PEET, of Jersey City, in the county of Hudson and State of New Jersey, have invented or produced a new and ornamental Design for Fire-Place Frame and Fender; and the following is declared to be a description of the same.

This design is made to represent bars crossing each other, and the panel between is filled with leaflet ornaments.

The entire design of this fire-place frame and fender is represented in the accompanying engraving.

The vertical bars *a a* intersect and cross the horizontal bars *b b*, and there are round ornaments *c* at the intersections. The panels between the bars are ornamented with rose-shaped figures *d d* and bars and leaflets in relief, as at *e e*, and there are ornamental brackets at *g*.

The horizontal bars *h* and vertical bars *i*,

forming the open-work of the fender, are of an ornamental appearance, corresponding generally to the fire-place frame, and there are leaflet ornaments *l* on diagonal stems, as represented. 25

I claim—

1. The ornamental design of the fire-place frame, consisting of the bars crossing each other and the rose-shaped and bar ornaments, 30 as represented.

2. The design of the open-work fender, composed of the intersecting bars with the leaflet and diagonal-stem ornaments, as described and shown. 35

Signed by me this 25th day of May, A. D. 1880.

WM. C. PEET.
